[57] CLAIM

The ornamental design for a shoe outsole, as shown and described.

DESCRIPTION

FIG. 1 is a bottom plan view of a shoe outsole showing my new design;

FIG. 2 is a side elevational view of the lateral side of the shoe outsole shown in FIG. 1;

FIG. 3 is a side elevational view of the medial side of the shoe outsole shown in FIG. 1;

FIG. 4 is a cross sectional view of the shoe outsole taken across section 4—4 shown in FIG. 1;

FIG. 5 is a cross sectional view of the shoe outsole taken across section 5—5 shown in FIG. 1;

FIG. 6 is a cross sectional view of the shoe outsole taken across section 6—6 shown in FIG. 1; and,

FIG. 7 is a cross sectional view of the shoe outsole taken across section 7—7 shown in FIG. 1.

The broken line showing of a shoe upper in FIGS. 2 and 3, is for illustrative purposes only and forms no part of the claimed design. In addition, the cross sectional views illustrate the surface of the shoe outsole only.
